UNITED STATES PATENT OFFICE.

HARRY W. BROWN, OF CHICAGO, ILLINOIS, ASSIGNOR TO JAMES G. TRAINER, OF CHICAGO, ILLINOIS.

RECORDING-LOCK.

1,127,178.

Specification of Letters Patent.

Patented Feb. 2, 1915.

Application filed January 24, 1910. Serial No. 539,820.

To all whom it may concern:

Be it known that I, HARRY W. BROWN, a citizen of the United States, residing at Chicago, in the county of Cook and State 5 of Illinois, have invented certain new and useful Improvements in Recording-Locks, of which the following is a specification.

The object of my invention is to provide an improved construction of recording lock 10 in which the insertion of keys held by different persons will effect different contacts to establish connections for making records distinguished from each other; and further to provide for the momentary closing of a 15 circuit embracing such contact devices and identifying recording means and other means such as time recording devices, such closing of the circuit resulting from the turning of the inserted key though not being directly caused thereby, the idea being to have the turning of the key set and trip circuit-closing means so that the key can not be manipulated either to prevent the closing 20 of the circuit or to hold the same closed. 25 In addition to such features as above indicated I provide means for throwing the bolt of the lock from the inside and making a contact by insertion of the key for such purpose which contact provides for a different connection than that established by insertion of any of the outside keys. Further I provide for the closing of the circuit by a 30 watchman's key inserted from the outside and turned without throwing the bolt. 35 With the above stated and incidental objects in view the invention consists in certain novel features of construction and combinations of parts the essential elements whereof are recited in the appended claims 40 and a preferred form of embodiment of which is described in detail hereinafter and fully illustrated in the drawings which accompany and form part of this specification. 45 Of said drawings Figure 1 represents the complete lock as applied to the door or other closure the mechanism being shown in elevation with the inclosing casing for the most part in section, full lines illustrating the normal condition of certain movable parts whereas dotted lines show an intermediate condition thereof brought about through partial turning of an inserted key; Fig. 2 shows some of the parts of Fig. 1 in 50 similar elevation but differently positioned

as when the circuit is momentarily closed; Fig. 3 is a section taken substantially on the line 3—3 of Fig. 1; Fig. 4 is a section taken substantially on the line 4—4 of Fig. 3; Fig. 5 shows certain of the parts in perspective and detached; Fig. 6 is a section taken substantially on the line 6—6 of Fig. 1; Fig. 7 is a section taken substantially on the line 7—7 of Fig. 1; Fig. 8 is a section taken substantially on the line 8—8 of Fig. 1; and Figs. 9, 10 and 11 show the different keys for the lock.

The reference letter A designates the base plate of the lock and A' the front plate through which the bolt B works, said bolt 70 having a shank B' sliding on the base plate A along a rib α formed thereon and having shoulders alternately engaged by a latch C pivoted to the bolt and yieldingly held to a central position by a flat spring C', Fig. 4, 75 said latch serving to hold the bolt against movement from either of its extreme positions otherwise than by the turning of a key. To the base plate A there is secured by screws α' Fig. 6, the body D of an ordinary key structure such as the Yale in which body is journaled the barrel D'. In the construction here shown this barrel is bifurcated at the inner end and there is slidingly engaged with the bifurcated portion a plunger E square in cross section and confined against removal from the barrel by a cap D² secured over the inner end of the barrel and formed with a square opening through which said plunger slides, the latter having 80 a foot e extending under the cap. This plunger E extends through a short tubular shaft or sleeve F journaled at one end in the base plate A and at the other in a frame plate A² said sleeve being internally grooved 85 to receive the corners of the plunger and maintain an engagement with the latter which will cause it to always rotate therewith while at the same time the plunger may slide through the sleeve. The latter 90 carries a crank arm F', Fig. 4, lying against the base plate A and adapted to work under the bolt and having a roller stud f to operate against transverse shoulders of the bolt and throw the same back and forth, said 100 roller or the end of the crank arm also acting against the latch C to disengage the same from the shoulders of the rib α . A set of keys of different lengths but of corresponding formation as to bits are adapted 105 110

to be inserted in the barrel D the slot of which leads to the outer end of the plunger E so that the key when inserted strikes against the foot *e* of the plunger and forces it in to a greater or less degree according to the length of the key.

Fig. 9 illustrates the key of the well known Yale kind which is adapted to be used in the manner above described and the dotted lines in this figure denote the different lengths of the keys.

It is obvious that the turning of any fully inserted key rotates the barrel D' and the differentially movable plunger E, which latter, whatever its longitudinal position, serves as an actuator for turning the sleeve F and crank arm F' to throw the bolt from locked to unlocked position, or vice versa.

The inner end of the differentially movable actuator E bears against a pivoted arm G, and forms a positioning element for shifting such arm to one or the other of its various positions through its differential movement as determined by the particular key employed, the free end of such arm constituting an electric contact device or movable electrode. This arm is pivoted to the fixed frame work, as shown at *g*, and has applied to it a spring *g'* impelling it toward the base plate A and thus pushing the plunger E outward to the position shown in full lines in Fig. 6. The free end of this arm which is somewhat broadened for contact purposes, is adapted to move along a series of contact terminals *h* secured in a standard H of insulating material secured to the base plate A by a suitable bracket H'. Wires *h'* run from the respective terminal contacts *h* to binding posts H² respectively, see Fig. 1, which binding posts may be wired to any suitable form of electric recording mechanism whereby imprints of different characters or other records will be made to show what particular key was used when the lock was operated. Normally the free end of the arm G lies against the base plate A out of contact with any of the terminals *h*. I have here shown four terminals for the keys carried by different persons who are to enter and leave by the door to which this recording lock is applied, these being the rear four terminals.

In Fig. 6 the dotted lines illustrate the effect of introducing the longest one of the four keys, the arm being represented as moved back to the farthest point where it would contact with the rearmost terminal. The shortest of these keys would move the arm to contact with the second terminal and the keys of intermediate lengths would move the arm to engagement with the third and fourth terminals respectively. The first terminal is provided for making a connection by the introduction of an inside key such as shown in Fig. 10 so that when the

door is locked or unlocked from the inside this will be recorded as distinguished from the records of locking or unlocking from the outside. This inside key does not operate through the same device as do the outside keys in throwing the bolt. A separate sleeve or barrel I is journaled in the base plate A and frame plate A², Figs. 1, 3 and 4, such sleeve or barrel carrying a crank arm I' just like the crank arm F' and having a similar roller stud *i* to act against the shoulder of the bolt and against the latch C. This key barrel or sleeve I is slotted along one side to accommodate the fin or elongated bit *i*² of the key I³, Fig. 10, so that the barrel or sleeve will be rotated by the key. There is an enlargement at the inner end of the slot and into that enlargement normally projects a lug *j* on one arm of a bell crank lever J which is pivoted to the frame plate A² and pressed by a spring *j'* in a direction to thrust the lug into said enlargement as illustrated in Fig. 1. The key I³ is beveled on one side as shown at *i*⁵ in Fig. 10, the bevel extending across the end of the fin or bit *i*³ and adapted when the key is inserted to act against the lug *j* and rock the bell crank lever J against the stress of the spring *j'*. The long arm of said bell crank lever has a beveled lug *j*³, Fig. 5, which extends under the movable contact arm G and is adapted upon the rocking of the lever to engage a beveled lug *g*³ on said arm to move the latter into engagement with the first of the series of terminal contacts *h* and thus make the desired connection to record the operation of the lock from the inside.

Passing now to the means for momentarily closing the circuit through such contact devices or otherwise, there is journaled upon a post or arbor *k* projecting from the base plate A, a cylindrical metal block K cut away on one side as illustrated at *k'* and there is secured to a strip or bar of insulation K¹ on the base plate A a spring contact strip K² whose free end normally stands in the cut away part *k'* without contact with the block K. The latter has applied to it a spiral spring *k*³, Fig. 4, whereby it is normally held in the position illustrated in Figs. 1 and 4, a pin *k*⁶ carried by it contacting with a lug *k*⁷ on the base plate as illustrated in Fig. 4. It is obvious that a partial rotation of said cylindrical block will bring its periphery into contact with the strip K² and furthermore that release of the block will cause its spring to break the contact. Now said block has secured to it a cam-shaped disk K⁴ with an abrupt radial shoulder *k*⁸ adapted to be acted upon by a wiper pawl M for the purpose of momentarily closing the circuit in the manner just mentioned. This wiper pawl is pivoted on the end of a curved arm or lever M' pivoted at its inner end to the frame

plate A² as shown at *m* and normally held back by a spring M² which is connected at one end to said frame plate and at the other end to the wiper pawl M so that the spring 5 not only serves to retract the curved arm or lever but also holds said wiper pawl against a pin *m'* on the lever as illustrated in Fig. 1. The normal position of the wiper pawl as shown is behind the cam disk K⁴. 10 The rocking of the lever M' against the stress of the spring M² will cause the curved edge of this wiper pawl to contact with and wipe over the curved edge of the cam disk in rear of the radial shoulder *k*⁸, the wiper 15 pawl rocking on this pivot against the stress of said spring M² to the position indicated by dotted lines in Fig. 1 which shows the point of the wiper pawl just about to pass the point of the cam disk. As soon as these 20 points have passed each other then the wiper pawl snaps in front of the radial shoulder *k*⁸ and on the return of the lever M' acts against said shoulder turning the cylindrical block K against the stress of its spring 25 *k*³ to the position shown in Fig. 2 where the point of the wiper pawl is about to again escape the point of the cam disk moving in the opposite direction. Immediately upon such escape the cam contact block K is 30 turned to normal by its spring. It will therefore be obvious that in order to effect a momentary contact in closing the circuit it is only necessary that the key when turned shall retract the lever M' and release the 35 same. As to keys thus far referred to, this effect is produced through the medium of the bolt, which being thrown by the key in one direction or the other first sets or retracts the lever M' to position to cause the 40 operation of the circuit-closing block K, and then trips or releases said lever before the bolt reaches its extreme of movement. Thus the bolt carries a pivoted wiper pawl or 45 flipper N having a tail piece *n* working between studs *n'* on the bolt. The tapered end of this wiper pawl or flipper is adapted to act upon a pin or stud *m'* on a branch of the lever M'. Normally with the bolt retracted this flipper stands away from said 50 stud or pin as illustrated in Fig. 1, full lines. When the bolt is moved outward the flipper advances and contacts with said stud or pin its tail being thrown against the forward stud *n'* and by wiping over said pin retracts the lever M'. Before the bolt reaches the 55 end of its movement the flipper N escapes past the stud or pin *m'* whereupon the lever M' springs back and as its wiper pawl M has been carried in front of the shoulder *k*⁸ 60 it will operate to turn the contact block K and then release the same. When the bolt is drawn back exactly the same effect is produced, the other inclined face of the flipper N acting against the stud or pin *m'*.

The night watchman's key P, Fig. 11, is inserted in a third barrel or sleeve P' journaled in the base plate A and the frame plate A² and this sleeve is slotted similarly to the inside key sleeve or barrel I and the key P has an elongated bit or fin *p* similar to 70 that on the key I³ though it does not perform a similar function as to any setting of the contact arm G. The latter is not affected by insertion or turning of the night watchman's key. The bit of the night 75 watchman's key by engaging the slot of the barrel is enabled to turn the latter and this barrel carries a cam P² of the snail back variety which cam is adapted to act upon a pin or stud *p'* projecting from the lever M' 80 through a slot in the frame plate A². Turning of the night watchman's key by rotating this cam serves to set and trip said lever M' and thus effect the oscillation of the contact 85 block K in the same manner as the turning of the keys heretofore described. Thus the cam first retracts the lever until its wiper pawl M passes the point of the disk K⁴ and then releases said lever with the same effect 90 as already described.

In order to compel the full operation of any key to project the bolt or retract the same I provide a locking arm Q pivoted to the frame plate A² at *q* and connected by a spring *q*² with the lever M', said arm having 95 a curved finger *q*³ lying against said lever. The rear end of the arm is formed with a square lug *q*⁴ which is adapted to coöperate with the rear stud *n'* on the bolt which stud is elongated for the purpose. Normally this 100 lug stands off from the line of travel of said stud as shown in Fig. 1 but as a key is turned to move the bolt and the lever M' is at the same time advanced, the pin *n'* having moved in front of the lug *q*⁴, the spring *q*² 105 will be put under tension and as soon the bolt moves far enough to carry its pin or stud *n'* beyond the square lug the latter will snap over said pin thereby locking the bolt against reverse movement. When the bolt is 110 moved from a retracted to a locking position the side of the lug toward its pivot will thus engage the pin *n'* to lock the bolt, and when the bolt is thrown back or withdrawn the other side of the lug will come into engagement with said pin. However, at the extreme of either movement of the bolt the lever M' is of course restored and acting 115 against the curved finger *q*³ of the locking arm Q will disengage the latter from the stud *n'* of the bolt or move it out of the path of the latter. Turning of the barrel I otherwise than by the key I³ is prevented by the engagement of the lug *j* in the slot of the barrel, and turning of the barrel P' otherwise than by key P is similarly prevented by the engagement of a lug *p*⁶, on a spring-actuated bell-crank lever P⁶, with the slot 120 125

in said barrel, the lug adapted to be displaced by the beveled end of the fin *p* in said key *P*.

It will now be seen that the above described devices are well calculated to thoroughly fulfil the objects primarily stated, yet it is to be understood that the constructions here shown are susceptible of modification within the scope of the invention.

What is claimed is:

1. A lock comprising a bolt, a member for throwing the bolt, a series of contact terminals, an electrode movable over said contact terminals, and a key operated actuator for said electrode, said electrode being displaced by said actuator to contact with one or another of said contact terminals according to different keys employed, said actuator when operated by a key also engaging the bolt throwing member to actuate the latter.

2. A lock comprising a bolt, means for throwing the same, a series of contact terminals, an electrode in the form of a pivoted arm movable over said contact terminals, and a key operated displaceable actuator connected to the bolt throwing means to operate the same when the key is operated, said electrode being displaced by said actuator to contact with one or another of said contact terminals according to different lengths of keys employed.

3. A lock comprising a bolt, means for throwing the same, a series of contact terminals, an electrode in the form of a pivoted arm adapted to separately engage said contact terminals, a key-barrel, a slidable member rotating therewith to actuate the bolt-throwing means and by its sliding movement positioning said electrode, and keys of different lengths for sliding said member.

4. In a lock, the combination with a bolt and electric contact devices, of a key operating the latter by inward thrust and the bolt by turning.

5. In a lock, the combination with a bolt, and a series of contact terminals, of a common movable contact and differently dimensioned keys for differentially positioning the latter by a movement in one direction and for throwing the bolt by a movement in a different direction.

6. A lock having means for operating it from opposite sides, together with devices for effecting electrical connections, the connections differing when the lock is operated from different sides.

7. A lock comprising a bolt, means for throwing the same, a series of contact terminals, a movable electrode coöperating with said contact terminals, a key operated rotatable and longitudinally displaceable actuator connected to the bolt throwing means

to operate the same by its rotative movements, said actuator engaging the electrode when longitudinally displaced to move the same into coöperative relation with respect to one or another of said contact terminals according to the length of key employed, and independent means for throwing the bolt, said independent means also operating to position the electrode into coöperative relation with one of said contact terminals.

8. A lock comprising a bolt, means for throwing the same, a series of contact terminals, an electrode in the form of a pivoted arm adapted to separately engage said contact terminals, a key-barrel, a slidable member rotating therewith to actuate the bolt-throwing means and by its sliding movement positioning said electrode, keys of different lengths for sliding said member, auxiliary bolt-throwing means, a key for operating the same from the opposite side of the lock from that where the first-mentioned keys are applied, and means for positioning the electrode by said last mentioned key differently than it is positioned by the first-mentioned key.

9. A lock comprising a bolt, means for throwing the same, a series of contact terminals, an electrode in the form of a pivoted arm adapted to separately engage said contact terminals, a key-barrel, a slidable member rotating therewith to actuate the bolt-throwing means and by its sliding movement positioning said electrode, keys of different lengths for sliding said member, auxiliary bolt-throwing means, a key for operating the same from the opposite side of the lock from that where the first-mentioned keys are applied, and a lever operated by said key by the insertion thereof said lever having a cam acting upon the electrode to position the same differently from its positioning by the other keys.

10. In a lock, the combination with a key-operated element, of a circuit-closing device, and means set and tripped by said key-operated element to momentarily close the circuit.

11. In a lock, the combination with key-operated elements, of an oscillatory circuit-closing device, and means set and tripped by said key-operated elements to momentarily close the circuit.

12. In a lock, the combination with separate key-operated elements, of a circuit-closing device, a common means set and tripped by said key-operated elements to momentarily close the circuit.

13. In a lock, the combination with key-operated elements, a contact spring, an oscillatory block normally spring-held out of engagement with said spring, and means for oscillating the block by the key-operated elements.

14. In a lock, the combination with key-

operated elements, a contact spring, an oscillatory block normally spring-held out of engagement with said spring and having a radial shoulder, a spring-drawn lever carrying a wiper-pawl, and means for moving said lever in opposition to its spring, by the key-operated element, and thereby engaging the pawl with said shoulder, and then releasing the lever; substantially as and for the purpose described.

15. In a lock, the combination with key-operated elements, a contact spring, an oscillatory block normally spring-held out of engagement with said spring and having a radial shoulder, a spring-drawn lever carrying a wiper-pawl, and means for moving said lever in opposition to its spring, by the key-operated element, and thereby engaging the pawl with said shoulder, and then releasing the lever, said means comprising a double-acting wiper-pawl for engaging said lever.

20. In a lock, the combination with key-operated elements, a contact spring, an oscillatory block normally spring-held out of engagement with said spring and having a radial shoulder, a spring-drawn lever carrying a wiper-pawl, and a lock for the key-operated elements in the form of a spring-held arm normally retracted by said lever.

25. In a lock of the character described, the combination of a series of contact terminals, a pivoted arm forming an electrode to coöperate with said contact terminals, and key operated means to set said arm to contact with one or another of said contact terminals according to the length of key employed.

30. In a lock of the character described, a series of contact terminals, an electrode in the form of a pivoted arm adapted to separately engage said terminals, a key barrel, a member having sliding engagement with said barrel for positioning said electrode by its sliding movement, and keys of different length for sliding said member.

19. In a lock, the combination with a bolt and electric contact devices, of a key operating the latter by inward thrust and controlling by a turning movement the throwing of the bolt.

20. A lock comprising a bolt, means for throwing the same, a series of contact terminals, an electrode in the form of a pivoted arm adapted to separately engage said contact terminals, a key barrel, a slideable member rotating therewith to control the means for throwing the bolt and by its sliding movement positioning said electrode, and keys of different length for sliding said member.

21. A lock comprising a bolt, means for throwing the same, a series of contact terminals, an electrode in the form of a pivoted arm adapted to separately engage said terminals, a key barrel, a slideable member rotating therewith to control the means for throwing the bolt and by its longitudinal movement positioning said electrode, keys of different length for sliding said member, auxiliary bolt throwing means, a key for operating the same from the opposite side of the lock from that where the first mentioned keys are applied, another electric terminal and means operated by said second mentioned key for placing the electrode in contact with said last mentioned terminal.

22. In a recording door lock, the combination with a lock mechanism mounted on the door, of a time-recording mechanism mounted outside the lock casing, electrically actuated means for operating said recording mechanism, a plurality of circuits for said electrically actuated means, and key actuated circuit closing means carried by said lock mechanism, and a key individual to each circuit for operating said key actuated means.
